VULCANIZING APPARATUS

Roy W. Brown and George P. Bosomworth,
Akron, Ohio, assignors to The Firestone Tire &
Rubber Company, Akron, Ohio, a corporation
of Ohio

Application December 9, 1931. Serial No. 579,974

10 Claims. (Cl. 18—17)

This invention relates to vulcanizing apparatus, and more especially it relates to individual type watchcase vulcanizers, the invention being directed primarily to improved means for opening and closing the cover of a watchcase vulcanizer.

The chief objects of the invention are to provide means for raising and lowering a vulcanizer cover whereby the initial opening movement and final closing movement is substantially normal to the cover; to provide means for automatically moving a pivotally suspended vulcanizer cover to determinate angular position with relation to its supporting means and to the vulcanizer; to provide automatically operated safety mechanism for holding the cover in open position; and to provide for exerting a powerful pressure on a closed vulcanizer cover to compress the work within the vulcanizer. In general the invention aims to prevent the occurrence of defective work due to distortion or displacement thereof in the vulcanizer upon being engaged by the vulcanizer cover, which frequently occurs in vulcanizers having hinged covers.

25 Of the accompanying drawing:

Figure 1 is a front elevation of vulcanizing apparatus embodying the invention in its preferred form, a part of the vulcanizer being broken away; and

30 Figure 2 is a section on the line 2—2 of Figure 1, the vulcanizer being shown in elevation.

Referring to the drawing, a vulcanizer comprising a base section or housing 10 and cover 11 is mounted upon a suitable supporting frame- 35 work 12. A locking ring 13 is mounted upon base member 10 and has a bayonet-joint connection with the cover 11 for locking the latter in place upon the base member 10. Rack and pinion mechanism 14 provided with an operating handle 40 15 is provided for manually turning the locking ring 13 angularly to lock or release the cover 11.

Rising from the framework 12 at the rear of the vulcanizer is an upright framework 16, the upper end portion of which has two parallel out- 45 standing brackets 17, 17 between which a double-acting fluid pressure operated cylinder 18 is swiveled on an axis that is transverse to and to one side of the axis of the vulcanizer. Pressure fluid is conducted to the respective ends of the cylinder 18 through flexible pipes 19, 20, which pipes extend to a control valve 21 at the front of the vulcanizer. The valve 21 is provided with a crank 22 for manually operating the same.

The cylinder 18 is provided with a piston rod 24 50 that extends downwardly from the cylinder and

has a yoke 25 mounted upon its lower end, which yoke is connected to a transversely disposed hinge pin 26 mounted in the outer end portion of an arm 27 that is pivotally mounted at 28 upon a bracket 29 secured to the upright framework 16. 60 The arm 27 comprises a pair of laterally spaced-apart plates 27^a, 27^a suitably connected and braced by the hinge pin 26 and by a shouldered bolt 23 in its outer end, the yoke 25 being disposed between the plates 27^a. The vulcanizer cover 11 65 is pivotally suspended from the hinge pin 26 by means of a link 30 that is mounted on the hinge pin between the forks of the yoke 25.

The arrangement is such that when the vulcanizer is closed, as shown in full lines in the 70 drawing, the arm 27 is substantially in horizontal position or slightly downwardly inclined toward its free end, with the result that upward movement of the piston rod 24, which results in upward movement of the free end of the arm 75 27, raises the cover 12 substantially axially, normal to the plane of separation of the cover and base member 10. The direction of the cover is reversed in its final closing movement so that it descends squarely upon the work, and does not 80 distort or displace the same.

In the extreme uppermost position of the cover 11 it is desirable to tilt the same so as to give easy access to the interior of the vulcanizer for removing the finished work and mounting un- 85 vulcanized work therein, and for presenting the mold section in the cover at a convenient angle to permit treatment thereof, such as soaping to prevent sticking of the work. To this end the plates 27^a of the arm 27 are provided on their 90 bottom margins adjacent the pivots 28, with re- spective brackets 31, 31 that are formed with concave sockets adapted to engage the respective end portions of a hinge pin 32 that is mounted upon the vulcanizer cover 11 at the rear thereof. 95 The arrangement is such that the cover 11 moves substantially axially upward in its initial opening movement until the hinge pin 32 is engaged by the brackets 31 and then moves angularly with the arm 27 until it reaches the extreme open po- 100 sition shown in broken lines in Figure 2.

As a safety feature to prevent accidental lowering of the cover 11 from its elevated position, from failure or leakage of the fluid pressure supply to the cylinder 18, a U-shaped yoke or loop 105 34 is pivotally attached by its respective end portions to the respective brackets 17.

The closed middle portion of the yoke 34 is positioned below the cylinder 18 in front of the same, in the path of the front end of the arm 110

27, which front end is beveled or oblique as shown so that in the raising of the arm 27 it will engage and move the yoke forward until the lower edge of the arm is above the yoke, the latter then 5 dropping back into engagement with a recess 35 formed in the lower edge of the arm. For moving the yoke 34 from in front of the arm 27 automatically when it is desired to lower the arm, the yoke is provided with a rearwardly extending bracket arm 36, the rear end of which is connected by a cable 37 to a lever 38 constituting a part of the valve 21 and operated by the crank 22 of the latter when the crank is turned to admit pressure fluid to the upper end of the cylinder 18. An adjustable stop 38 in a bracket 39 on the framework 16 is positioned to be engaged by the bracket arm 36 and determines the normal position of the yoke 34.

It is highly desirable that in the lowering of 20 the cover 11 onto the vulcanizer base member 10, it register accurately with the locking ring 13 since misalignment of the cover would require that it again be raised before it could be aligned. To prevent such misalignment from swaying of 25 the cover on the pivot pin 26, the link 30 is formed with forwardly extending lugs 40, 41 which are disposed on opposite sides of the pivot pin 26 and engaged by a lever 42 that is pivotally mounted at 43 on the front of the yoke 25. A tension spring 30 44 connected to the lever 42 near the free end thereof extends rearwardly and has its other end connected to a bracket 45 mounted upon one of the side plates 27^a of the arm 27. The arrangement is such that when the lever 42 engages both 35 lugs 40, 41 of the link 30 it will prevent swaying of the cover on the pivot pin 26, and yieldingly hold the cover in a horizontal plane when the pin 32 of the cover is free of the brackets 31. Tilting of the cover in either direction causes the 40 lever 42 to engage only one of the lugs 40, 41, with the result that the link 30 is yieldingly urged in the opposite direction by reason of the positions of the lugs on opposite sides of the pivot pin 26.

In the operation of the apparatus, assuming 45 the vulcanizer to be in the closed position shown in full lines in the drawings, the locking ring 13 is turned angularly to unlock the cover 11, and then the crank 22 of valve 21 is turned to admit pressure fluid to the lower end of cylinder 18, causing the piston rod 24 of the latter to move upwardly. This raises the free end of the arm 27, and the cover 11, the spring 44 and lever 42 keeping the cover 11 in horizontal position during the initial upward movement so that it 50 separates from the vulcanizer base 10 by a movement of translation parallel to the axis thereof. Continued angular movement of the arm 27 brings the pin 32 of the cover 11 into engagement with brackets 31 on the arm so that the cover is 55 tilted to the position shown in broken lines in Figure 2 when the piston rod 24 reaches its fully retracted position. Approaching its extreme raised position the forward end of the arm 27 passes the yoke 34 and the latter moves 60 under the end of the arm as shown so as to prevent accidental lowering of the arm.

With the cover raised the interior of the vulcanizer is freely accessible. To lower the cover, the crank 22 is turned to admit pressure fluid 70 to the upper end of the cylinder 18 and concurrently to vent the lower end of the cylinder. Turning of the crank 22 also swings the yoke 34 outwardly from under the end of the arm 27, by reason of the cable 37 connecting the yoke to the crank, with the result that the arm 27 is

80 moved angularly downwardly in reverse direction to the opening movement. As soon as the arm 27 is lowered sufficiently to free the cover pin 32 from the brackets 31, the spring 44 and lever 42 operate to stop any swaying of the cover 11 and bring it to rest in horizontal position so that it descends squarely upon the work in the vulcanizer and registers accurately with the locking ring 13. The fluid pressure in the cylinder 18 is sufficient to exert a powerful downward pressure upon the cover 11 so as to compress the work within the vulcanizer. The locking ring is then turned to lock the cover 11 in place, after which the vulcanizing operation may commence.

85 The invention is simple in construction and in operation. It prevents the displacing or distorting of the work in the vulcanizer from contact with the vulcanizer cover, and achieves the other objects set forth in the foregoing statement of objects.

90 Modifications may be resorted to without departing from the spirit of the invention, or the scope of the appended claims which are not limited wholly to the specific construction shown and described.

95 What is claimed is:

100 1. In combination with vulcanizing apparatus comprising a base and a removable cover, an angularly movable arm to the free end of which the cover is pivotally connected, means for angularly moving said arm to raise and lower the cover, and yielding means for maintaining the cover parallel to the base during part of the angular movement of the arm, and means for disposing the cover at an angle to the base after the cover has reached an elevated position with respect to said base.

105 2. In combination with a vulcanizing apparatus comprising a base and a removable cover, an angularly movable arm to the free end of which the cover is pivotally connected, means for angularly moving said arm to raise and lower the cover with relation to the vulcanizer, yielding means normally operative to cause the cover to assume a non-swinging horizontal position when near the base of the vulcanizer, and means associated with the arm to cause the cover to assume a tilted position in its extreme raised position.

110 3. In combination with a vulcanizing apparatus comprising a removable cover, a pivotally mounted arm to the free end of which the cover is pivotally connected, fluid pressure means for moving the arm up and down to raise and lower the cover, and a yoke automatically engageable under the arm in its uppermost position to support said arm against failure of the fluid pressure means.

115 4. A combination as defined in claim 3 including means automatically disengaging the yoke from the arm upon reversing of the fluid pressure to cause descent of the arm.

120 5. In combination with a vulcanizing apparatus comprising a removable cover, a pivotally mounted arm to the free end of which the cover is suspended, a fluid pressure cylinder having its piston rod connected to the free end of said arm to raise and lower the same, a valve controlling the pressure fluid supply to said cylinder, a yoke automatically engageable under the arm in its uppermost position to support it against failure of the fluid pressure, and means connecting the yoke with the fluid pressure control valve for disengaging the yoke from the arm concurrently

with the charging of the cylinder to lower the arm.

6. In combination with a vulcanizing apparatus comprising a removable cover, a pivotally mounted arm, a hinge pin in the free end thereof, and a fluid pressure cylinder having a piston rod connected to said hinge pin, for raising and lowering the arm, the cover being pivotally suspended from said hinge pin.

10 7. In combination with a vulcanizing apparatus comprising a removable cover, a pivotally mounted arm, a fluid pressure cylinder having its piston rod connected to the free end of said arm for raising and lowering the same, the cover being pivotally suspended from the free end of said arm, and means mounted upon the piston rod and engaging the cover structure for maintaining the latter in fixed angular position with relation to the vulcanizer during a part at least 20 of the movement of the arm.

8. In combination with a vulcanizing apparatus comprising a removable cover, a pivotally mounted arm, a fluid pressure cylinder, a hinge pin in the free end of said arm to which the

25

piston rod of the fluid pressure cylinder is connected for raising and lowering said arm, a link pivotally suspended from said hinge pin and connected to said cover, and means mounted upon the end portion of the piston rod and yieldingly engaging the link for preventing swaying of the cover.

9. In combination with a vulcanizing apparatus comprising a removable cover, a pivotally mounted arm, a fluid pressure cylinder, a hinge pin in the free end of said arm to which the piston rod of the cylinder is pivotally connected, for raising and lowering said arm, a link pivotally suspended from said hinge pin and connected to said cover, a lever mounted upon the end portion of the piston rod and engaging said link, and yielding means urging the lever against the link to prevent swaying of the cover.

10. A combination as defined in claim 9 in which link is formed with a pair of lugs disposed on opposite sides of the hinge pin, which lugs are engaged by the lever.
